United States Patent Office.

ALBERT H. MERSHON, OF PHILADELPHIA, PENNSYLVANIA.

Letters Patent No. 77,512, dated May 5, 1868.

IMPROVEMENT IN DAMPERS FOR HOT-AIR FURNACES.

The Schedule referred to in these Letters Patent and making part of the same.

TO ALL WHOM IT MAY CONCERN:

Be it known that I, ALBERT H. MERSHON, of Philadelphia, in the State of Pennsylvania, have invented a new and useful Improvement on my Mode of Regulating the Draught of Hot-Air Furnaces, for which I hold a patent from the United States, dated May 29, 1866, combined with a dust-flue; and I do hereby declare that the following is a full, clear, and exact description of the construction and operation of the same, reference being had to the annexed drawings, making a part of this specification.

I attach to the chain A, forming part of my patent aforesaid, the chain B, at a point, E, at a distance below the pulleys D D, greater than the range of motion of the flue-door F, passing said chain B over the pulleys D D, and attaching it with a hook at the point C, to the sloping door F, hinged above at G, and made sufficiently heavy to close by its own weight when there is no tension on the chain B, in the same manner as the draught-door H, forming part of my patent aforesaid, closes by its own weight. The door F is lighter than the door H. The door F opens into a horizontal flue, I, which connects with the furnace-flue K. The damper M, which is opened or closed at pleasure by means of the handle O, separates the flue I from the ash-pit N. This damper is always closed, except when the fire is raked, when it is opened to allow the dust to pass in the flue I, from which it is removed at pleasure through the door F.

The operation of my invention, thus described, is as follows: The draught-door H being heavier than the flue-door F, when said draught-door H is closed, its weight in closing, through the attachment and arrangement of the chain B, and pulleys D D and chain A, opens the flue-door F, and admits a body of cold air into the horizontal flue I, which passes into the furnace-flue K, (the damper M being closed,) and checks the draught of the furnace at the mouth of the pipe L. Again, the draught-door H being opened, the chain B is slackened, and the flue-door F closes by its own weight, thus permitting an uninterrupted draught through the furnace and drums and pipe L, into the flue K.

What I claim as my invention, and desire to secure by Letters Patent, is—

The chain B, pulleys D D, door F, horizontal flue I, and damper M, when combined and constructed substantially as and for the purposes herein described.

ALBERT H. MERSHON.
